UNITED STATES PATENT OFFICE.

THEODORE A. WILLARD, OF CLEVELAND, OHIO.

SEPARATOR-SLICING MACHINE.

1,297,767.

Specification of Letters Patent. Patented Mar. 18, 1919.

Application filed June 9, 1915. Serial No. 32,994.

To all whom it may concern:

Be it known that I, THEODORE A. WILLARD, a citizen of the United States, residing at Cleveland, in the county of Cuyahoga and 5 State of Ohio, have invented a certain new and useful Improvement in Separator-Slicing Machines, of which the following is a full, clear, and exact description.

This invention relates to a separator slicing machine adapted particularly for cutting or slicing storage battery separators from a semi-soft or yieldable block of rubber, with the rubber semi-vulcanized or softened by heat. 10 The main object of the invention is to provide a slicing machine which is adapted to efficiently slice a block of the character stated, and which cuts the block into thin flat smooth-surfaced separator sections which 15 are uniform in thickness.

With the ordinary slicing machine in use at the present time for other purposes, smooth separators of uniform thickness could not be cut from the block for several 20 reasons, but especially as the block would be bulged out of shape by the knife which would also compress or force the block back and at some strokes would not cut at all and at other strokes would possibly cut off sections of many times the thickness desired.

To avoid all the objections or difficulties, I provide certain novel instrumentalities including a spring-actuated feed mechanism which acts on the rear end of the block in 25 such a way as to maintain the block under very heavy but substantially uniform or constant compression. Additionally, I provide in connection with this feed mechanism a gage board against which the forward end of 30 the block is yieldingly pressed and in fact forced with considerable pressure. Still further, I provide certain novel clamping means which securely clamps the block on all four sides adjacent the end which is being cut by 35 the knife, this clamping means releasing the block at each retraction of the blade, so that it can be fed forward the exact or predetermined distance desired.

The invention comprises certain other features of construction, including the arrangement and construction of the support and guide for the block or stock being sliced, and means for automatically stopping the feeding action when the follower bearing against

the rear end of the block reaches a certain 55 position with reference to the cutting blade.

The invention may be further briefly summarized as consisting in certain novel details of constructions and combinations and arrangements of parts, which will be described 60 in the specification and set forth in the appended claims.

In the accompanying sheets of drawings Figure 1 is a side view of a forward portion of the machine with the stock holder in section substantially along the line 1-1 of Fig. 2; Fig. 2 is a top plan view of a portion of the machine showing particularly the stock-supporting and guiding means and the feeding mechanism; Fig. 3 is a view of the cutting end of the machine looking toward the left of Fig. 1; Fig. 4 is a view of the same part of the machine looking toward the left of Fig. 3; Fig. 5 is a view of a portion of the inner side of the stock support, showing 75 the same substantially as it appears when viewed from the left of Fig. 7; Fig. 6 is a sectional view through the knife-holder, knife and gage board, the section being taken substantially along the line 6-6 of Fig. 1; Fig. 7 is a sectional view through the stock holder and guide, the section being taken substantially along the line 7-7 of Fig. 2; and Fig. 8 is a view looking toward the left of Fig. 2, showing in end elevation the stock holder 80 and feed mechanism.

The machine constructed in accordance with my invention, includes a bed 10, which may be of any suitable construction. This bed accommodates a reciprocating head 11 90 which may be actuated by any suitable mechanism, a part of which is shown at 11^a in Fig. 1, and carries a slide or knife-holder 12 provided with an inclined knife 13 and with a portion beneath the knife and constituting a gage board 14 which is parallel with the knife but is offset slightly from the edge of the latter an amount equal substantially to the thickness of the separators which are to be cut from the block. 95

Just beneath the knife and extending parallel thereto is an adjustable member 14^a, having an inturned portion, whose inner face is parallel with the inner face of the gage board 14, and is adapted to engage the 105 block to be cut close to the edge of the knife. When the knife is sharpened this member will be adjusted toward the edge of the knife.

so as to maintain the slot between the member and the edge of the knife of substantially predetermined or constant width.

Extending outwardly from the forward 5 end of the bed, at right angles to the plane of reciprocation of the knife, is a long stock holder and guide 15 which is rectangular in cross-section and is provided with a base or bottom 15^a and two sides 15^b and 15^c, the 10 latter being of less depth than the side 15^b. This long box-like stock holder is preferably turned so that the base 15^a is at an angle of about 45 degrees with respect to the horizontal, and is supported at its inner 15 end by being securely bolted to an L-shaped standard 16 projecting upwardly from the bed near the plane of reciprocation of the knife. This stock holder is adapted to receive a block or body 17 which is adapted 20 to be sliced into separator sections and is preferably composed of rubber and fibrous material, with the rubber in a soft or semi-vulcanized condition. The block is only semi-vulcanized when sliced, because the 25 separators are very thin, and when sliced from a hard or completely vulcanized block they curl up and cannot be flattened unless they are softened by a heating process, which has an unsatisfactory effect on the 30 separators.

The feed mechanism acts on a follower or compressor 18 which engages the end of the block and travels along the stock holder and guide. This follower has a part 19 in the 35 form of a nut projecting downwardly from a slot 20 in the base of the stock holder and engaging a threaded feed screw or shaft 21 which extends substantially throughout the length of the stock holder parallel to the 40 slot 20. (See particularly Fig. 2). The construction of the follower will be explained later in more detail. This feed screw is not actuated positively or turned an exact or predetermined distance at each 45 stroke of the cutting mechanism as is generally the case in feeding mechanisms for various kinds of machine tools, but at each stroke of the knife is turned an amount depending upon the degree of compression 50 of the block and somewhat upon the hardness of the block and the condition of the knife edge.

The mechanism for actuating this feed screw includes a long shaft 22, which is 55 parallel to the feed screw, but extends forwardly beyond the latter beneath and slightly beyond the knife. This shaft 22, which is supported in suitable bearings at its front and rear ends, is provided at its 60 forward end with a projecting arm 23 which is engaged by a member 24 secured to the lower part of the reciprocating holder 12 for the knife and gage board. Each time the knife is retracted the shaft 22 is turned 65 or rocked a predetermined amount. The

rear end of the shaft 22 has secured to it a depending arm 25 carrying on its side a lug or boss 26 which may be secured in any one of a number of spaced openings with which the arm 25 is provided. Extending loosely 70 through this lug or boss 26 is a rod 27 which at its forward end is connected to an arm 28 loosely mounted on the rear or outer end of the feed screw 21. Surrounding this rod 27 is a coil spring 30, one end of which engages the lug or boss 26, while the other end engages a nut 31 adjustably mounted on the rod 27, the latter being threaded so as to accommodate this nut and to permit it to be adjusted along the rod. Fixed to the 80 feed screw or shaft 21 is a ratchet wheel 32, the teeth of which are adapted to be engaged by cooperating ratchet pawl 33 pivotally mounted on the arm 28 and spring-pressed 85 toward the ratchet wheel. This pawl 33 turns the ratchet wheel forwardly at each forward stroke of the arm 28, while a similar spring-pressed pivoted pawl 34 prevents reverse movement of the ratchet wheel.

It will be observed that the connection between the arms 25 and 28 includes the coil spring 30, and that the amount of movement which is transmitted to the arm 28 by the arm 25 will depend upon the strength or the amount of compression normally in the 95 spring 30. When the shaft 22 and the arm 25 are turned, the spring 30 will first be compressed a certain amount and thence will shift the arm 28 and the threaded feed screw. If the nut 31 is adjusted, the 100 amount of movement which is transmitted to the arm 28 at each forward throw of the arm 25 is increased or decreased, depending on the direction in which the screw is adjusted. This adjustment is of considerable importance to compensate for the gradual dulling of the knife blade, for as the blade becomes duller it has an increasing tendency to force back the block and cut thinner sections. If, however, the nut 31 is 105 adjusted from time to time toward the arm 25 so as to shorten the spring or increase its normal compression, the threaded shaft will be fed forwardly a slightly greater amount with each forward adjustment of the nut, 110 with the result that the compression of the block which is being cut is increased a sufficient amount to compensate for the increased dullness of the blade.

The block is maintained under compression while it is being sliced, as before stated, and this spring 30 and the nut 31 not only admit of adjustment to compensate for the increasing dullness of the knife as the slicing progresses, but it maintains a substantially uniform degree of compression in the block, thus compensating for variations in degree of hardness in the same block or different blocks which are successively placed in the machine and sliced.

The block is compressed between the follower and the gage board 14, which, as before stated, is reciprocated with the knife and is offset somewhat therefrom an amount 5 depending upon the thickness of the separator. This gage board not only gages the thickness of cut, but it is essential in order that the soft or yieldable block may be maintained under compression.

- 10 A spring 22^a (see Fig. 2), which surrounds the shaft 22 near its outer end, serves to return the shaft 22 to normal position after each feeding stroke. The return movement is limited or stopped by an abutment 15 28^a which is engaged by the arm 28. (See Fig. 8.) The shaft 22 and arm 25 positively return the bolt 27 and arm 28 to normal position, due to the fact that during 20 the reverse swinging movement of the arm 25 the boss 26 engages an abutment preferably in the form of a pair of nuts 31^a on the outer part of the rod 27 near the boss 26.

In order that smooth uniform sections may be cut from the block, it is necessary 25 that the latter be securely clamped on all four sides at a point or plane very near the knife. This is accomplished by the means of a V-shaped clamping device 35 having two arms at right angles to each other and 30 adapted to engage one corner of the block and two sides of the same, and to force the block firmly against the bottom 15^a and rear side 15^b of the stock holder, with the result that clamping pressure will be applied to 35 all four sides of the block. This V-shaped clamp 35 is pivotally connected to a block or plate 36, which is adjustably secured to an arm 37 pivoted at 38 to the frame of the machine near the plane of reciprocation of 40 the knife. The clamp is pulled inwardly toward the corner of the block 17 firmly but yieldingly by a stiff coil spring 40 and by a rod 41, which is pivotally connected to the arm 37 and passes through the upper part of 45 the standard 16 and through the coil spring, the latter engaging a nut at the outer end of the rod 41 and also engaging the standard, as shown. The plate 36 will be adjusted along the arm 37 so as to adapt the clamp 35 50 to the size of the block 17 and to properly position the same with respect thereof.

Between the upper end of the arm 37 and the standard 16 are two toggle arms 42 and 43, which, at their point of union or connection, carry a roller 44. Normally these two arms are at slight angles to each other, with the center of the roller some distance above the plane passing through the pivoting centers of the arms 42 and 43, *i. e.*, the 55 pivotal centers about which the two arms 42 and 43 turn. These arms are held in this position by the spring 40 when the clamp 35 engages the block or when a section is being cut from the end of the block.

60 For the purpose of drawing the clamp

away from the block so that it may be fed forwardly after the separator or section has been cut from the block, the knife-holder 12 is provided at the top thereof with a cam 45, which on the retraction of the blade engages the roller 44, forcing it downwardly, spreading the toggle arms and swinging the arm 37 so as to draw the clamp away from the block. This takes place while the knife is retracting, and as soon as the clamp is released from the block the block is fed forwardly a certain amount by the feeding mechanism, whereupon, upon the forward movement of the knife and before the knife 70 engages the block to make the next cut, the cam 45 moves beyond the roller 44, which immediately springs upward under the action of the spring 40, permitting the latter to bring the clamp into clamping engagement with the block. This results in 80 a clean cut being made by the knife and prevents distortion or bulging of the block when the knife engages the same, and results also in all the sections being of substantial 85 uniform thickness.

90 Preferably the side or wall 15^c of the stock support and guide is provided on its inner face, near the V-shaped clamping device 35, with a leaf spring 46, (see Figs. 2 and 5) which spring bears against one side 95 of the block near the end being cut or sliced and holds the same up against the face 15^b of the stock support when the V-shaped clamp is retracted or released from the block 17, to permit the same to be fed forwardly.

100 In addition to the parts above described, I have provided means for automatically stopping the feed of the follower 18 and the block 17 when the follower reaches a point 105 adjacent the clamp. This can be best explained by reference to Figs. 2, 5 and 7, from which it will be observed that the member 19 which engages the threaded feed screw 21 is supported by an endwise movable plunger 47 provided at its upper end with a yoke 47^a, having an opening which receives a cam 47^b mounted on a transverse shaft 48, supported in suitable upright bearings on the rear part of the follower. When 110 the shaft 48 is turned to one position, the cam lowers the plunger 47 and causes the member 19 to engage the threaded feed screw. When, however, the shaft is turned a certain amount from said position, a 115 spring 49 surrounding the plunger shifts the nut 19 out of engagement with the feed screw. The shaft carrying the cam can be turned manually by means of a handle 50, and it is turned automatically to stop the 120 feeding action when the follower reaches a predetermined position. This last is accomplished by providing on the side 15^c of the stock guide near the clamp 35 a projection 51 so positioned that it will be engaged by 130

a depending finger or cam 52 mounted on the shaft just above the side 15° of the stock support. The rocking of this finger turns the shaft 48 and permits the spring 49 to 5 elevate the nut 19 from the feed screw so as to stop the feeding action. This prevents injury to the parts by the follower feeding forwardly too far.

While I have shown the preferred embodiment of my invention, I do not desire to be confined to the exact details shown, but aim in my claims to cover all modifications, which do not involve a departure from the spirit and scope of my invention in its 15 broadest aspect.

Having thus described my invention, what I claim is:—

1. In a slicing machine, a cutter, means for operating the same, means for intermittently feeding a yieldable body at right angles to the cutting plane, and means for producing between the feeding operations a clamping pressure at substantially all points about said body in a plane adjacent the 25 plane of the cutter.

2. In a slicing machine, a cutter, means for operating the same, a stock holder adapted to accommodate a yieldable body substantially rectangular in cross-section, means for 30 feeding the stock along the stock holder, and means for producing clamping pressure on all four sides of the body so that said body is clamped substantially all around the same adjacent the cutter.

3. In a slicing machine, a cutter, means for operating the same, a stock holder adapted to accommodate a yieldable body adapted to be cut, said stock holder having angularly disposed sides, means for feeding the stock 40 intermittently along said holder, and means engaging two sides of said body and acting during the cutting operations to force said body into a corner formed by two adjacent sides of the stock holder, said means engaging the stock adjacent the cutter.

4. In a slicing machine, a cutter, means for operating the same, a stock holder adapted to accommodate a yieldable rectangular body, means for feeding the body along the 50 stock holder, and means engaging the two sides of the body at a corner thereof and serving to force said body into the angle formed by two sides of the stock holder, said means producing a clamping pressure on all 55 sides of the body adjacent the cutter during the cutting operations.

5. In a slicing machine, a cutter, means for operating the same, a stock holder adapted to accommodate a yieldable body, means for 60 feeding said body along the stock holder, a V-shaped clamp adapted to engage said body adjacent the cutter during the cutting operations and force the same against the stock holder and thereby produce a clamping pres-

sure around the body close to the cutter, and 65 a movable support for said clamp.

6. In a slicing machine, a cutter, means for operating the same, a stock holder adapted to accommodate a yieldable body, means for feeding said body along the stock holder, a 70 clamp adapted to engage said body during the cutting operation and force the same against the stockholder and thereby produce a clamping pressure around the body close to the cutter, a movable support for said 75 clamp, means acting on said support to draw the clamp yieldingly against the body, and means for shifting the support for said clamp so as to release the body from said clamp.

7. In a slicing machine, a cutter, means for operating the same, a stock holder at right angles to the cutting plane adapted to accommodate a yieldable body, means for feeding said body along the stock holder, a pivoted arm adjacent the plane of reciprocation of the cutter, a clamp supported by said arm and adapted to engage the body adjacent the cutter and force the same against the stock holder and thereby produce a clamping pressure 85 around the body close to the cutter, and means for pressing said clamp yieldingly against said body during the cutting operations.

8. In a slicing machine, a cutter, means for 90 operating the same, a stock holder at right angles to the cutter and adapted to accommodate a yieldable body, and feeding mechanism acting on said body for feeding the body along said stock holder and for maintaining said body under compression, said feeding mechanism comprising an actuating member, and yieldable means between said member and the body.

9. In a slicing machine, a cutter, means for 95 operating the same, a stock holder, means for intermittently feeding the stock along said stock holder, comprising a feeding member acting on the stock, an actuating member therefor, and means comprising a spring 110 for transmitting movement between said actuating member and said feeding member.

10. In a slicing machine, a cutter, means for operating the same, a stock holder, means for intermittently feeding the stock along 115 said stock holder, said means comprising an actuating member, means comprising a spring for transmitting movement between said actuating member and the stock, and an adjustable abutment for the spring.

11. In a slicing machine, a cutter, means for operating the same, a stock holder adapted to accommodate a yieldable stock, means for feeding stock along said stock holder comprising a feed screw, a follower engaging the stock and operatively connected with the feed screw, an intermittently moving actuating member, and a spring between said

member and the feed screw for transmitting movement between the same.

12. In a slicing machine, a cutter, means for operating the same, a stock holder adapted to accommodate a yieldable body, means for feeding the stock along said holder comprising a feed screw, a follower engaging the stock and operatively connected to the feed screw, an actuating member for the feed screw, means for intermittently actuating said member, and means connecting said member and said feed screw comprising a spring and an adjustable abutment for the spring.

13. In a slicing machine, a cutter, means for operating the same, a stock holder adapted to accommodate a yieldable body, means for feeding stock along said stock holder comprising a feed screw, a follower engaging the stock and operatively connected to the feed screw, a shaft, means for intermittently turning the shaft, means for transmitting movement from said shaft to the feed screw comprising a compression spring adapted to be compressed by the turning of the shaft, and means for adjusting the normal compression of the spring.

14. In a slicing machine, a cutter, means for operating the same, a stock holder at right angles to the cutter, feeding mechanism for feeding the stock along said stock holder, said feeding mechanism comprising a feed screw, a follower adapted to engage the stock and operatively connected to the feed screw, a shaft, means for turning said shaft a predetermined amount at each stroke of the cutter in one direction, means for transmitting movement between the shaft and the feed screw, and means in said movement transmitting means for varying the extent of movement which is transmitted to the feed screw.

15. In a slicing machine, a cutter, means for operating the same, a stock holder at right angles to the cutter and adapted to accommodate a yieldable block to be cut, a gage board adjacent the cutter and offset therefrom, and feeding mechanism for intermittently feeding stock along said stock holder into engagement with the gage board.

16. In a slicing machine, a cutter, means for operating the same, a gage board movable with the cutter and offset therefrom, a stock holder at right angles to the cutter and adapted to accommodate a yieldable stock, and means for feeding the stock intermittently along the stock holder and for pressing the stock against the gage board.

17. In a slicing machine, a cutter, means for operating the same, a stock holder at right angles to the cutter and adapted to accommodate a yieldable block to be cut, a gage board adjacent the cutter and offset therefrom, and a spring actuated feeding

mechanism for compressing stock against 65 the gage board and for intermittently feeding the stock along the stock holder.

18. In a slicing machine, a cutter, means for operating the same, a stock holder adapted to accommodate a body to be sliced, means 70 for feeding the body along the stock holder, a clamp for engaging the body adjacent the cutter during the cutting operations, means for causing the clamp to move into and out of clamping engagement with the body, and 75 yieldable means adjacent said clamp for pressing the body against the stock holder when the clamp is out of clamping engagement with the body.

19. In a slicing machine, a cutter, means 80 for operating the same, a stock holder adapted to accommodate a body to be sliced, means for feeding the body along the stock holder, a clamp for engaging the body and for forcing the same against a portion of the stock 85 holder, means for moving the clamp into and out of clamping engagement with the said body, and a spring supported by said stock holder and adapted to engage said body to press the same against the stock holder when 90 the clamp is out of clamping engagement with the body.

20. In a slicing machine, a cutter adapted to cut a yieldable body, means for operating 95 the cutter, means for supporting said yieldable body, a gage movable with said cutter and offset therefrom, means for feeding the body against said gage, said gage having an adjustable member movable toward and from the edge of the cutter.

21. In a slicing machine, a cutter, means for operating the same, a support for yieldable stock to be cut, a gage movable with said cutter, means for feeding the stock toward the cutter and forcing the same in engagement with the gage, said gage comprising a part fixed relative to the cutter and an adjustable member carried thereby and movable toward and from the edge of the cutter.

22. In a slicing machine, a cutter, means 110 for operating the same, a stock holder adapted to accommodate stock to be cut, means for feeding the stock along the stock holder, said means comprising a follower adapted to engage the rear end of the stock, an actuating member therefor extending lengthwise of the stock-holder and adapted to be engaged by said follower, and means for automatically disengaging said members when the follower reaches a predetermined position 115 with respect to the cutter.

23. In a slicing machine, a cutter, means for operating the same, a stock holder at right angles to the cutter and adapted to accommodate the stock to be cut, feeding 125 mechanism for feeding the stock along the stock holder, said feeding mechanism comprising a follower adapted to engage the

rear end of the stock, a feed screw extending lengthwise of the stock holder, said follower having a movable member adapted to engage the feed screw, and means for automatically stopping the feed of the stock when the follower reaches a predetermined point with respect to the cutter, said means comprising a movable member carried by the follower and controlling the position of said part engaged in the feed screw and a member on the

stock holder adapted to engage said movable member of the follower and to shift the same.

In testimony whereof, I hereunto affix my signature in the presence of two witnesses. 15
